JOSEPH BURGER, OF BROOKLYN, NEW YORK

HEEL

Application filed December 17, 1929. Serial No. 414,630.

This machine relates particularly, though not exclusively, to heels of the type covered in Patent 1,792,965, of February 17, 1931, and made up of a wooden core with a covering of 5 leather or material having the characteristics or appearance of leather.

A special feature of such heels is that they are lined, streaked, striped or otherwise made up as the edges of the lifts of a solid leather 10 heel.

Such effects are obtained in various ways and one of such ways is to cut or groove definite lines in the leather or other heel covering, spaced approximately the thickness of 15 the regular leather lifts.

The present invention provides a machine for automatically pressing, cutting or forming the lift-edge grooves in the heel cover.

The objects of the invention, in addition 20 to the broad idea of providing a practical machine for the purpose stated are to provide such apparatus in simple, inexpensive form, which can be readily employed to effect the results desired, which can be controlled or 25 adjusted to meet different requirements and which will be generally efficient for the intended uses.

The objects mentioned and others, as will appear, are attained by certain novel features 30 of construction, combinations and relations of parts as hereinafter definitely pointed out and broadly claimed.

The drawings accompanying and forming part of this specification illustrate certain 35 practical embodiments of the invention, but as such are primarily for purposes of disclosure, it will be understood the structure may vary as regards these illustrations without departure from the true spirit and basic scope 40 of the invention.

Fig. 1 is a top plan view of a machine embodying the principles of the invention; Fig. 2 is a front or face view of the same; Fig. 3 is an enlarged cross-sectional detail, this view 45 being taken as on substantially the plane of line 3—3 of Fig. 2; Figs. 4 and 5 are edge and face views respectively of another form of the machine, differing from the first particularly in that rotary blades or knives are used 50 in place of reciprocating knives and are

adapted for lining across the breast of the heel as well as the outer heel surfaces; Fig. 6 is an edge view of the rotary blade employed in the embodiment of the machine shown in Figs. 4 and 5.

In the machine shown in Figs. 1 to 3 inclusive, the work of lining or grooving the heel is accomplished by reciprocating or oscillating blades or bars 7, the same being shown as all pivotally mounted at one end at 8 on a block 9 reciprocating in guides 10 under impulse of a link 11 connected with said block at 12 and actuated by an eccentric or crank 13. This crank is shown provided on one end of the shaft 14 suitably journaled in a bearing 15 and carrying a pulley 16 over which passes a belt 17 from a pulley 18 operated by motor 19.

The bars 7 are shown lying close together in flat face to face engagement against a back wall 20 which provides a gage against which the heel indicated at 21 is rested during the scoring, cutting or lining operation. These bars or blades may be of approximately the thickness of ordinary top lifts 75 and they are indicated as having edges 22. These edges may be sharp enough to actually cut into the heel or heel cover, or they may be relatively dull, so as to simply press or compact or groove the heel or heel material 80 without actually cutting into the same. The cutting or pressing operation also depends upon and can be controlled to an extent by the speed of movement and extent of reciprocation of the blades and the time and pressure with which the heel is engaged therewith.

A certain amount of pressure is usually desirable and for the purpose, presser bars 23 are shown pivoted at 24 and designed to bear at their free ends each on one of the lining blades. These presser bars may have sufficient weight of themselves or they may be "loaded" by means of special weights 25 shown as removably hooked to the free ends of the bars at 26.

The complete gang of marking or cutting blades may be used as a unit or only a single one or certain selected ones of the blades be operated. In the illustration, this is made 100

possible by permitting the blades and the pressure bars to be thrown upward and supported there out of service relation. This particular condition is illustrated in Figs. 1 and 2, where the front blade or "marker" as it may be generically termed and its pressure bar are shown both raised at their free ends and slidingly resting on a table or support 27 detachably secured at 28 on the top of a post 29. This support or rest 27 is made quickly detachable, so that it can be easily taken out of the way of the markers and pressure bars and then be slipped into supporting position beneath one or any selected number of the pairs of bars. The marker bars which have then been raised into this supported inactive position will simply oscillate idly over one edge of the support while the weights or pressure bars rest idly on the opposite edge or on top of the bars with which they ordinarily cooperate.

To prevent the markers from dropping down too low and to give them an initial or starting position, a lower support is shown at 30 detachably secured at 31 on the post. This second rest permits the markers to ride idly back and forth, when the machine is running, before the heel is inserted in the machine and does not interfere with the several markers rising more or less as required to follow the contour of the heel.

The ordinary method of using the machine is to insert the heel beneath the marker blades as in Fig. 2 with the heel seat end against the face of the gage plate and then by lifting and rotating the heel in this position to cause the markers to ride over and around the outer surface of the heel, producing the lift edge markings 32 in the course of such combined movements.

These markings, it will be obvious, may be made in the heel coverings or in the bare heels and may be accompanied then or later, as desired, with the application of paint, dye, coloring or finishing material to emphasize or otherwise bring out the lift-edge effect. In the case of grooving or scoring the bare uncovered heels, it will be understood that the cover, when afterwards applied, may be pressed into the score marks as disclosed in my application above referred to to bring out the lift edge effects.

The heels may be lined or marked either their full height or for a part of their height and they may be marked all in the single operation or in two or more separate operations. In Fig. 3, it will be seen that only the upper portion of the heel is being marked in this operation. This leaves the lower half of the heel free to be grasped as a handle for inserting and rotating the heel in the machine. After this first operation, the heel may be withdrawn and inserted in the machine in reversed relation with the top

lift end against the gage plate, using the heel seat end as a handle. This method has the additional advantage that these latter cuts or marks indicated at 32a will be put on parallel with the top lift, producing between the two sets of markings the wedge shaped appearing section 33 like the wedge used in full leather heels to give the desired "pitch", thus making the heel more than ever look like a solid leather lift heel.

In the second embodiment of the invention illustrated the markers are in the form of small rotary discs 7a journalled at 34 in the lower ends of slide bars 35 vertically independently shiftable in face to face relation within guides 36. These scoring, cutting or generally speaking "marking" wheels are each independently driven in the present disclosure by spring belts 37 operating in pulley grooves 38 in the sides of the discs and over suitable pulleys 39 on the motor shaft 40.

In this second embodiment, the downward movement of the markers is determined by a rest or stop 41 engaging shoulders at 42 in the edges of the slide bars 35. Shoulders 43 opposed to these first mentioned shoulders, by cooperation with the same stop, limit the lifting movements of these bars.

Any of the markers in this particular machine may be lifted up out of service position and then be secured in that relation by a bolt 44 threaded in the upper slide bracket 36 at 45 and adapted by the turning in this screw bearing to be projected into an opening or openings 46 in one or more of the lifted marker bars. One advantage in this second form of the invention, is that these small diameter markers may be used to score or otherwise mark the more or less transversely concave breast face 47 of the heel. At the same time it will be observed that these same markers may be employed to carry the markers entirely around about the outside of the heel. In fact, in this form of the invention, the complete periphery of the heel may be marked in one and the same continuing operation. Special means may be employed, if desired, for holding and shifting the heel under the markers, for instance, a rotary spindle or jack on which the heel is temporarily secured by its end face or faces.

It will be realized that both methods of marking have their own advantages, the reciprocating action being best for certain types of work and the rotary marking for other types of work. The first machine for example, may be employed for finishing the outer convex portions of the heel and the second machine be used for finishing the so-called inner or concave breast portions of the heel. The selective use of the two machines also may be determined by the nature of the heel coverings, the particular effects desired, etc.

What is claimed is:

1. A heel marking machine, comprising

- markers in side by side relation and independently shiftable to follow the outlines of a heel presented thereto and gage means for directing a heel in proper relation to said markers.
5. 2. A heel marking machine, comprising markers in side by side relation and independently shiftable to follow the outlines of a heel presented thereto and gage means for directing a heel in proper relation to said markers, said markers being independently shiftable into and out of service relation.
10. 3. A heel marking machine, comprising markers in side by side relation and independently shiftable to follow the outlines of a heel presented thereto, gage means for directing a heel in proper relation to said markers, said markers being independently shiftable into and out of service relation and means for releasably holding a selected marker or markers in such out of service relation.
15. 4. A heel marking machine, comprising markers in side by side relation and independently shiftable to follow the outlines of a heel presented thereto, gage means for directing a heel in proper relation to said markers, said markers being independently shiftable into and out of service relation, means for releasably holding a selected marker or markers in such out of service relation and means for imparting heel marking movements to the marker or markers in service.
20. 5. A heel marking machine, comprising markers in side by side relation and independently shiftable to follow the outlines of a heel presented thereto, gage means for directing a heel in proper relation to said markers and means for imparting heel marking movements to said independently shiftable heel shape conforming markers.
25. 6. A heel marking machine, comprising markers in side by side relation and independently shiftable to follow the outlines of a heel presented thereto, gage means for directing a heel in proper relation to said markers and means for positioning said independently shiftable markers in initial relation in readiness to conform to a heel shape presented thereto.
30. 7. A heel marking machine, comprising a gage adapted to be engaged by a heel block and independently supported heel markers operating in substantial parallelism with said gage means to thereby conform in position to the outlines of a heel presented to the gage.
35. 8. In a machine of the character disclosed, a series of heel marking devices mounted in independently movable relation, enabling them to individually follow the contour of heels presented thereto and means for imparting heel marking movements to said devices irrespective of the individual self-adjustments of the same.
40. 9. In a machine of the character disclosed, a series of heel marking devices mounting in independently movable relation, enabling them to individually follow the contour of heels presented thereto, means for imparting heel marking movements to said devices irrespective of the individual self-adjustments of the same, means for supporting said marking devices in an initial relation ready for engagement by a heel and means for securing selected marking devices in inoperative relation away from said initial position.
45. 10. In a machine of the character disclosed, a series of heel marking devices mounted in independently movable relation, enabling them to individually follow the contour of heels presented thereto, means for imparting heel marking movements to said devices irrespective of the individual self-adjustments of the same, a rest for positioning the marking devices in initial relation and a second rest for supporting selected marking devices in inoperative relation free of the first rest.
50. 11. In a machine of the character disclosed, a series of heel marking devices mounted in independently movable relation, enabling them to individually follow the contour of heels presented thereto, means for imparting heel marking movements to said devices irrespective of the individual self-adjustments of the same, said marking devices having a gravitational movement, a rest for supporting the marking devices in a lower operating position and a second rest for supporting the marking devices in raised inoperative relation.
55. 12. In a machine of the character disclosed, a series of heel marking devices mounted in independently movable relation, enabling them to individually follow the contour of heels presented thereto, means for imparting heel marking movements to said devices irrespective of the individual self-adjustments of the same, said marking devices consisting of slidably supported bars having a reciprocating marking movement.
60. 13. A heel marking machine, comprising movable supported marking devices, means for imparting heel marking movements to said devices and means for weighting said marking devices.
65. 14. A heel marking machine, comprising movably supported marking devices, means for imparting heel marking movements to said devices, means for weighting said marking devices including hinged bars which can be shifted to an inoperative relation.
70. 15. A heel marking machine, comprising movably supported marking devices, means for imparting heel marking movements to said devices, means for weighting said marking devices including movable members and weights detachably connected with said movable members.

16. A heel marking machine comprising reciprocating blades mounted in independently shiftable relation to follow the contour of a heel and weighting bars riding on said blades.
17. A heel marking machine comprising reciprocating blades mounted in independently shiftable relation to follow the contour of a heel, weighting bars riding on said blades and weights detachably engageable with said weighting bars.
18. A heel marking machine, comprising reciprocating blades mounted in independently shiftable relation to follow the contour of a heel, weighting bars riding on said blades and means for supporting individual blades and weighting bars in inoperative relation.
19. The herein disclosed process of ornamenting a heel by means of a group of parallel marking devices, which consists in engaging the heel with said group of marking devices with one end of the heel, substantially parallel with said marking devices, then reversing the heel and engaging the opposite end portion of the heel with the marking devices in position substantially parallel with said last named end of the heel, whereby to mark the heel with two groups of marks substantially parallel respectively with the opposite ends of the heel.
20. The process of lining, a pitched heel to represent the edges of leather lifts and a wedge giving the "pitch" to the heel, which comprises presenting a heel having non-parallel end faces to a gang of substantially parallel markers, which range approximately half the height of the heel, first with the one end of the heel parallel to the markers and then with the opposite end of the heel parallel to said markers.
21. A machine of the character disclosed, comprising markers for lining the cover material of a shoe heel in simulation of the lift edges of a leather heel, said markers being disposed in side by side relation and means for enabling the engagement of said markers with the shoe heel covering material in predetermined gaged relation.
22. In a machine of the character disclosed, the combination of a series of grooving devices arranged to form grooves in the cover material for a shoe heel, said markers being spaced to line the grooves in general simulation of the lift edges of a leather heel and means for effecting the grooving engagement of said markers with heel cover material.

In testimony whereof I affix my signature.
JOSEPH BURGER.
